UNITED STATES PATENT OFFICE.

MAE WALLACE McCASTLINE, OF SYRACUSE, NEW YORK.

DESIGN FOR A SPOON, FORK, &c.

SPECIFICATION forming part of Design No. 24,897, dated June 18, 1895..

Application filed May 2, 1895. Serial No. 547,940. Term of patent 14 years.

To all whom it may concern:

Be it known that I, MAE WALLACE McCASTLINE, a citizen of the United States, residing in the city of Syracuse, county of Onondaga, 5 and State of New York, have invented and produced a new and original Design for Spoons, Forks, and Similar Articles, of which the following is a specification, reference being had to the accompanying drawings, in 10 which—

Figure 1 is a plan of a spoon embodying my design. Fig. 2 is a like view of the obverse thereof. Fig. 3 is a plan of a fork embodying said design. Fig. 4 is a like view of 15 the obverse thereof.

The leading features of my design consist of a chain of rings linked together and graded in diameter, and applied in relief to the han-

dle; a Maltese cross at one end and a Latin cross upon the bowl or blade of the spoon, 20 fork, knife or similar article, and upon the Latin cross is shown a crown of thorns.

—A— is the spoon or similar article, and —a— are the rings; —b—, the Maltese cross; —c—, the Latin cross, and —d— the crown 25 of thorns.

What I claim is—

A design for spoons, forks and similar articles, substantially as shown and described.

In witness whereof I have hereunto set my 30 hand this 10th day of April, 1894.

MAE WALLACE McCASTLINE.

In presence of—

C. W. SMITH,
HOWARD P. DENISON.
